(57) **CLAIM**

The ornamental design for a stand for an electronic device, as shown and described.

DESCRIPTION

FIG. 1 is a front perspective view of a stand for an electronic device showing my new design, the stand is comprised of a kickstand and a base and the base is attachable to a back side of an electronic device or a protective case;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the stand with the kickstand rotated;

FIG. 10 is a front perspective view of the stand with the kickstand in a closed position;

FIG. 11 is another front perspective view of the stand with the kickstand in a closed position;

FIG. 12 is a front perspective view of the stand illustrating the electronic device in broken lines; and,

FIG. 13 is a front perspective view of the stand with the kickstand in a closed position illustrating the electronic device in broken lines.

The broken line showing of environment is for illustrative purposes only and forms no part of the claimed design.
